UNITED STATES PATENT OFFICE.

HAROLD L. BLANCHARD, OF WHITINSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

TUBE FRAME.

Application filed November 9, 1923. Serial No. 673,738.

To all whom it may concern:

Be it known that I, HAROLD L. BLANCHARD, a citizen of the United States, residing at Whitinsville, in the county of Worcester and State of Massachusetts, have invented a new and useful Tube Frame, of which the following is a specification.

This invention relates to tube frames for Axminster looms and more particularly to an improved means for fastening the brackets or spool bearings to the ends of the tube frames.

One object of my invention is to provide a hollow tubular bar and bracket members with complementarily formed parts, by means of which the tube frame and bracket members are interlocked.

Another object of my invention is to provide a bracket which is very securely fastened to the frame but which may be readily removed therefrom without deforming either the tube frame or the bracket.

A more particular object of my invention is to provide a bracket formed of two parts so constructed as to have tube frame engaging ears of one part lying in a plane other than parallel to the ears of the other part, the ears being of varying cross section and arranged to be received by similarly formed openings in the walls of the tubular member.

With these and other objects in view, which will appear as the description proceeds, my invention resides in the combination and arrangement of parts hereinafter described and set forth in the claims.

In the drawings wherein one form of my invention is shown,

Fig. 1 is a front elevation of one end of a tube frame having my invention applied thereto,

Fig. 2 is a vertical transverse section taken on line 2—2 of Fig. 1 and

Fig. 3 is a perspective view showing one end of a tube frame and the associated bracket members in the position they assume before assembly.

Referring to the drawings, the body of the tube frame is shown as being formed of a hollow metal bar 10 of polygonal cross section having upper and lower horizontal walls 11 and 12, respectively, and parallel vertical walls 13 and 14, respectively. The yarn tubes 15 are carried by a strip of sheet metal 16 which is substantially L-shaped and en-

gages the outer faces of walls 12 and 14, the strips being held to the bar in any approved manner as by screws 17. A leaf spring 18 is screwed to the top of the tube frame and has an offset end provided with a friction 60 pad 19 to engage the head 20 of the spool 21 for the purpose of retarding rotation of the same.

My invention relates more particularly to the formation of the ends of the bar 10 and 65 the two members which together form the bracket or spool bearing. As shown in Fig. 3, the top wall 11 of the bar is provided with an opening 30 the outer end of which is comparatively narrow while the inner end 70 is wider. Walls 13 and 14 are provided with openings 31 and 32, similar to opening 30, which are preferably in alignment so that they may be stamped out by the same dies.

The spool bearing member 33 is formed at 75 the upper end thereof to receive the gudgeon of the spool 21 and the lower end is provided with a bent ear 34 so formed as to fit snugly in opening 30, that portion of the lower end of the member lying on each side of the ear 80 34 being arranged to engage the top of the tubular bar as shown in Fig. 1. The chain engaging member 35 has an offset upper tongue 36 received by the chain and has the lower end thereof provided with a pair of 85 ears 37 and 38, respectively, which are so formed as to fit snugly into openings 31 and 32. The members 33 and 35 are provided with registering holes 39 and 40, respectively.

When assembling the bracket the ear 34 90 is inserted in opening 30 after which the member 35 is positioned by inserting the ears 37 and 38 in openings 31 and 32, respectively. Screws 41 are then passed through countersunk openings 39 in the outer part 95 of the bracket and into the tapped holes 40, the two members being in this way united to form a rigid bracket.

It will be seen that I have provided an extremely simple bracket which is held to 100 the tube frame in such a way as to resist motion lengthwise of the tube frame, angularly with respect to the tube frame and transversely thereof either vertically or horizontally, while at the same time providing for a very ready means for removing the bracket. It will further be seen that the dovetailing of the ears and the associated openings permits the bracket to be secured to the frame without requiring screws to be 110

threaded into the hollow frame, and that all the parts can be made of stamped metal. While I have shown my invention as applied to a hollow tube, I do not wish to be limited to such a construction as the bracket could be used with any tube frame having dovetail recesses therein.

It will be observed that the interior of the tubular bar, when the latter is made hollow, 10 is smooth at the ends so that a wooden core extending the full length of the bar can be used if desired.

Having described my invention, it will be evident that changes and modifications may 15 be made by those skilled in the art without departing from the spirit and scope of the invention as set forth in the appended claims, and I do not wish to be otherwise limited to the details herein disclosed.

20 What I claim is:

1. In a tube frame for Axminster looms, a hollow bar polygonal in cross section and having the ends of adjacent walls provided with openings having sides oblique with respect to each other, and a bracket for said tubular member having ears extending therefrom and fitting snugly in said openings formed in the walls of the hollow bar.

2. In a tube frame for Axminster looms, 30 a hollow tubular member polygonal in cross section, a pair of bracket forming members secured together, one of said members having a dovetail connection with one of the walls of said tubular bar and the other member having dovetail connection with opposite walls of the tubular bar.

3. In a tube frame for Axminster looms,

a transverse bar extending lengthwise of the tube frame, a bracket for said bar, and interlocking dovetail connections between the bar and bracket and formed integrally with said bar and bracket and lying in angularly disposed planes to prevent angular, transverse and longitudinal movement of the bracket with respect to the bar.

4. In a tube frame for Axminster looms, 40 a hollow tubular bar having adjacent angularly disposed walls, a pair of bracket forming members therefor, one of said members having a dovetailed portion to lie within dovetailed openings in one of the walls of the bar to restrain said member against transverse motion with respect to the bar in one direction, the other member having dovetailed portions to lie in dovetailed openings in other walls of the bar to restrain transverse motion with respect to the bar in another direction, and means to secure said members together to form a bracket which is restrained against transverse motion with respect to the tubular bar in any direction.

5. In a tube frame for Axminster looms, 45 a bar polygonal in cross section, a pair of bracket forming members, ears formed on said members and received in recesses 50 formed in the bar to define dovetail connections between the bar and the members, and means to secure the members together, said dovetail connections forming the only connection between the bar and the members.

55 In testimony whereof I have hereunto affixed my signature.

HAROLD L. BLANCHARD.
